UNITED STATES PATENT OFFICE.

LOUIS H. BRINKMAN, OF GLEN RIDGE, NEW JERSEY, ASSIGNOR, BY MESNE ASSIGNMENTS, TO BALTIMORE TUBE COMPANY, INCORPORATED, A CORPORATION OF VIRGINIA.

APPARATUS FOR AND METHOD OF CORRUGATING METAL TUBES.

1,210,895.

Specification of Letters Patent. Patented Jan. 2, 1917.

Application filed October 15, 1914. Serial No. 866,758.

To all whom it may concern:

Be it known that I, LOUIS H. BRINKMAN, a citizen of the United States, and a resident of Glen Ridge, county of Essex, State 5 of New Jersey, have invented certain new and useful Improvements in Apparatus for and Methods of Corrugating Metal Tubes, of which the following is a specification.

My invention relates to apparatus for and 10 method of corrugating metal tubes.

The invention is especially useful for helically corrugating hot metal tubes.

I have heretofore provided apparatus for helically corrugating tubes, such apparatus 15 being the subject matter of United States Letters Patent Number 1,120,269 for tube-corrugating apparatus, granted on December 8, 1914, upon an application filed by me on January 11, 1913, Serial No. 741,390. The 20 apparatus of said patent is very efficient in corrugating cold tubes, but it produces a very heavy twisting force in the metal being folded which, to a very considerable extent, twists the metal as it is being folded to 25 aid in folding it. But I have found that hot tubes can hardly stand the twisting force produced in the tube by the use of said machine when used for deeply corrugating tubes. So that one of the objects of this invention is to provide a durable and efficient 30 machine that can be used to form very deep helical corrugations in hot metal tubes. The machine is capable of corrugating tubes without subjecting the metal being folded 35 to such a severe twisting force as takes place in the operation of my said other machine, and the tubes corrugated by the present machine are not twisted to the extent to which they are twisted by the other machine.

40 When the metal is hot it can be folded or corrugated without twisting it to the extent to which it is desirable to twist cold tubes in corrugating them, and, furthermore, as stated, the hot metal will not stand so great 45 a twisting force.

Another object of the invention is to provide a machine of the above character having means which will continuously act to successively and momentarily grip the tube 50 along a helical line at a progressively shifting short portion thereof, and release it.

Another object of the invention is to provide a tube-corrugating apparatus by means

of which corrugated tubes of considerable length and having extremely deep corrugations, may be made, the lengths of the corrugated tubes being limited only by the lengths of the tubes obtainable to be corrugated. 55

A further object of the invention is to provide a method of corrugating metal tubes, 60 and especially hot metal tubes.

In order that my invention may be more readily understood and further objects of the invention more fully appear, I will first describe a machine for drawing hot 65 metal tubes embodying the present preferred form of my improvements in tube-corrugating apparatus and by the operation of which my preferred method of corrugating hot tubes may be carried out. 70

In the accompanying drawings illustrating said machine, Figure 1 is a longitudinal elevation of the machine; Fig. 2 is a top plan view of the same; Fig. 3 is an end elevation of the left-hand end of the machine looking 75 in the direction of arrow A; Fig. 4 is a sectional elevation taken on line 4-4 of Fig. 2; Fig. 5 is an enlarged longitudinal section taken on line 5-5 of Fig. 1; Fig. 6 is a cross-sectional view taken on line 6-6 of 80 Fig. 5; Figs. 7 and 8 show details; Fig. 9 is a view taken on line 9-9 of Fig. 1; Fig. 10 is a section taken on line 10-10 of Fig. 9; Fig. 11 shows a tube being corrugated; and Fig. 12 shows an enlarged side elevation of 85 a portion of the machine shown in Fig. 1, with certain of the parts in section.

Referring to Figs. 1 to 4, inclusive, 1 is a table or bench having two longitudinal side pieces 2, 2', to the top of which are secured 90 two parallel pieces 3, 3' forming a guideway or track for a traveling carriage 4 provided with parallel grooves 5, 5' slidingly fitting the guideway, so that the carriage may move back and forth thereon. The table is provided with end brackets 6, 6' in which is mounted a main drive shaft 7 driven at the right-hand end of the machine by any suitable means, such as a pulley 8. This main drive shaft 7 is geared to a swaging apparatus hereinafter referred to, carrying the corrugating tools, to rotate the same, and is also geared to the carriage 4 to move the same along the track, each as follows: The said shaft 7 is provided at its left-hand end 95 with a gear 9 keyed to rotate therewith, 100

105

meshing with a gear 10 mounted on a hollow spindle 11 (Fig. 5) journaled in a frame 12 and carrying at its other end the corrugating tools of the swaging apparatus hereinafter referred to. Also keyed to the end 5 of the shaft 7 adjacent the gear 9 is a beveled pinion 13 which meshes with beveled pinion 14 mounted on a stub shaft journaled in bracket 15, the stub shaft being provided 10 at its other end with a beveled pinion 16 meshing with another pinion 17 keyed to a worm shaft 18 mounted in a suitable bracket 19 below the trackway and having a worm 20 which drives a worm wheel 21 keyed to a threaded or lead shaft 22. This lead shaft extends through a threaded nut 23 (Fig. 4) mounted in the lower end of the carriage 4, so that as the threaded shaft 20 is rotated through the above-mentioned 15 gearing, the carriage is moved along the trackway.

The main shaft 7 also drives a rotating chuck 24 to which the forward end of mandrel 59 and tube 60 are secured by set screws 25 61, 61'. The chuck is rotated in the same direction as the corrugating tools of the swager, but at a different rate. In the present machine the chuck is driven at a greater rate of speed than the tools. To rotate the 30 chuck the shaft is provided with a keyway extending along its length, in which slides a key 25 secured to a gear 26 which, through the intermediation of pinions 27 and 28, drives gear 29 loosely mounted (Figs. 9 and 35 10) on a sleeve 62 keyed to stub shaft 63 journaled in bearings 30, 30' on the carriage. The pinions 27 and 28 are also journaled on the carriage in bearings formed in the vertical webs 31, 31' of the carriage. The stub 40 shaft 63 is provided with a nut and washer 64 in engagement with the bearing 30' to take the drag of the tube secured to the chuck 24 on the other end of the stub shaft. The gear 29 and sleeve 62 are connected 45 through springs 67 secured at one end to the gear and at the other end to projections 68 from the sleeve. The gear is also provided with lateral projecting lugs or stops 69 and 70 serving to limit the movement of 50 the sleeve relative to the gear. The object of this connection is to permit the chuck to yield at certain times, as hereinafter explained.

In order that the gear 26 will move along 55 the shaft 7 as the carriage is moved back and forth, the vertical webs 31, 31' (Figs. 2, 4 and 10) are each provided with bearings or sleeves 32, 32' surrounding the shaft 7, one on each side of the gear 26. By 60 means of this arrangement the gear 26 is made to follow the movements of the carriage, and at the same time is caused to rotate with the shaft 7 to drive the rotary chuck 24.

65 Referring to Figs. 5, 6 and 8 showing the

construction of the swaging apparatus carrying the corrugating tools, it will be seen that the hollow spindle 11 (Fig. 5) driven by gear 10 (as heretofore mentioned), is journaled in a suitable bearing 35 formed in the stationary frame 12 secured to the table 1. This hollow spindle 11 is provided with an enlarged head 36 (Figs. 5 and 8) slotted out to provide guides for any desired number of corrugating tool sections. In the present machine the head is provided with two cross slots at right angles to each other so as to provide four guide sectors 37, 38, 39, 40 (Fig. 8) acting as guides for the tool sections 41, 42, 43, 44 slidingly mounted 70 between the adjacent sectors so that they may move in and out radially therebetween. In order to hold the tool sections in place, an annular ring 45 (Fig. 5) is provided which is held in place by suitable bolts 46 (Fig. 6) extending into the guide sectors of the head 36. The guide sectors 37 to 40 are provided with shoulders 52 co-operating with shoulders 52' on the tool sections to limit the outward movement of the tools 75 due to the centrifugal force thereon. The frame 12 surrounding the head 36 is provided with an enlarged annular recess 47 in which is mounted an annular frame or ring 48 on the inner surface of which rolls 50 run. These rolls may be referred to as cam rolls and they are journaled in two rings 51, 51' which serve to tie the rolls together. The rings 51, 51' and the rolls 50 carried thereby are driven around in ring 48 by engagement of the curved outer ends 80 of the tool sections with the rolls 50 as the tool sections are rotated, so that the rolls 50 run around on the inner surface of ring 48 at a rate considerably less than the rate 85 of rotation of the tool sections, something less than half the rate.

When the spindle 11 is rotated the tool sections are thrown outward by centrifugal force against the shoulders 52, and as they simultaneously engage the cam rollers they are momentarily forced inwardly while under the rollers, and then thrown out again by the centrifugal force, etc., so that they are continuously and rapidly reciprocated as 90 the spindle is rotated. The inner ends of the tool or die sections are tapered as shown at 53 (Fig. 6) to permit of the desired radial movement of the sections, and the inner ends of the sections are provided with projections 95 54 to 58 which, when the die sections are assembled, form a thread or helical projection increasing in height and decreasing in pitch toward the finishing end of the die. In the preferred form of the invention as shown 100 herein (Fig. 5), the projections formed in each section of the die or tool constitute longitudinal sections of a continuous thread or helical projection progressively increasing 105 in height and decreasing in pitch, so that 110

when the die is assembled, the projections of the different die sections form such a helical projection.

It will be observed that the helical die

- 5 teeth or projections are so constructed that the advance projection 54 simply initiates in the tube a helical mark or groove along which the tube is to be folded, and that the advance convolution of the helical projection marks out along the length of the tube sufficient metal to form the axial sectional configuration of the desired fold in the ultimate product; that is, the distance along the groove between the adjacent points 54 and 15 55 is equal to the distance along the groove between the points 57 and 58, and equal to the distance between any intermediate successive points. The forward end of the tube before being placed in the machine is drawn 20 down slightly tapering, the extreme end of the tube fitting the mandrel 59 to which it is secured. The taper of the tube at this end is preferably substantially equal to the taper of a line connecting the projections of the die sections. It will be observed in Fig. 5 that such a line tapers inwardly toward the finishing end of the die. The object of this arrangement is to have the rear convolution or convolutions bring the metal 25 30 at the end of the taper firmly down on the mandrel so as to start corrugating the tube at this point by corrugations of gradually increasing depth, but of regular pitch, so as not to unduly strain and distort 35 the tube at the commencement of the operation, the forward projection of the die gradually engaging the tube from there on. The operation of the die sections to corrugate the tube will be more readily understood by describing the operation of the machine as a whole hereinafter. The rear end 40 of the tube rests upon a series of grooved rollers 33, 33' mounted on a frame 65, the tube being laid loosely on these rollers, and 45 extending through a gas furnace 66 and through the die to the rotary chuck 24.

If the chuck is rotated at 500 revolutions a minute to drive the tube at that rate, and the swager carrying the tools at 400 revolutions a minute, the tube will rotate once relative to the tools for every four revolutions of the tools, and since the swager is provided with four cam rolls rotating at say 130 revolutions per minute (something less than half the rate of the tools), there will be a relative rotation of 270 revolutions per minute between the tools and the rolls. The tools will therefore deliver 2.7 blows, or, in other words, grip the tube 2.7 times for each 55 60 rotation of the swager, so that the tube will be gripped and released 10.8 times for each complete rotation thereof relative to the tools. The lead screw is preferably geared so as to move the tube forward a distance 65 equal to the distance between the last two

teeth of the die for each rotation of the tube, in other words, to cause the tube to travel in conformity with the pitch of the tool helix.

In order to prevent the mandrel 59 from becoming unduly heated by the furnace through which it passes, and in order to also cool the corrugated or completed portion of the tube as it is formed on the mandrel, I provide suitable means for conducting a cooling fluid into the mandrel, and in the present form of the invention, I convey the cooling fluid to the forward end of the mandrel and cause it to flow back through the mandrel. In Fig. 12, I show a means of accomplishing this, which consists of a pipe 73 supported in any suitable rigid support or clamp 74 and extending through the mandrel to its forward end where the pipe is turned upward slightly at its forward end 85 to provide a nozzle for discharging the water into the mandrel, from whence the water flows rearwardly and is discharged at the rear end of the mandrel. The rear end of the pipe 73 is coupled up by any suitable 90 coupling, such as a piece of flexible tubing 75, with any suitable source of water supply represented by pipe 76.

The operation of the machine is as follows: The forward end of the tube 60 is run into the furnace and the water supply pipe 73 is then inserted in the mandrel secured in its support 74, and coupled up to the water supply, and the water turned on. After the tube 60 has been heated sufficiently, it is pushed through the die and the forward tapered end secured to the end of the mandrel by set screw 61. The tube having been secured in this manner, and its rear end resting on the rollers 33, 33', 100 the machine is started up, whereupon the chuck is rotated through the above-mentioned yieldable connection with gear wheel 29, the sectional dies are rotated by spindle 11, and the carriage commences to move forward due to the rotation of lead shaft 22. At this time the rear or finishing projection of the tool sections is in alinement with the end of the tapering portion of the tube, as shown in Fig. 5, and as the spindle 11 105 rotates, the tool sections are rapidly reciprocated, as heretofore explained, producing a rain of hammer blows upon the tube, the sections gripping the tube momentarily each time they are moved inward by the cam rollers, and releasing it momentarily each time they are thrown outward by centrifugal force after passing the rollers. The sections thus continuously act to momentarily grip and release the tube, and as the tube 110 is fed forward by the lead shaft, the convolutions which are being formed in the metal by the gripping action of the sectional dies, are gradually screwed along the gradually 115 deepening helix of the die section, increas- 120 125 130

ing in depth and decreasing in pitch so as to fold the metal deeper and deeper as the tube is acted upon by the die sections and rotated forward. The advance projection 5 of each section serves to produce a slight indentation along the tube in a helical line, and as the tube is fed forward, that portion of the corrugation which had been acted on by the advance convolution of the die gradually moves through the succeeding convolutions, being momentarily gripped and released until it reaches the final convolution of the die having the contour of the desired finished fold. It will now be seen 10 that the object of the resilient connection to the chuck is to permit the tube and mandrel to momentarily lag behind the positively driven member of the chuck during the momentary gripping periods, and to be snapped around to overcome the lag during 15 the moments of release. In this way the hot tube is relieved of the enormous twisting force that would occur if the dies were always in engagement with the metal or if 20 it were attempted to positively rotate the tube during the moments that it is gripped by the die. This operation is continued until the entire tube has been corrugated, the tube being heated by the furnace as it 25 is drawn through the same. It is advisable, if not necessary, in operating upon hot tubes in this manner, to cool the die or tool sections, and for this purpose I deliver, 30 through passage 49 extending through frame 35 12 and ring 48 a cooling fluid to the recess 47 in which a sufficient depth of water or other cooling fluid is maintained to cool the die sections as they rotate through the same. By regulating the amount of water fed to 40 the recess 47 through the passage 49 the water may be kept below the die sections so that they are cooled only by conduction through the guiding parts, or it may be kept at such depth as to permit the outer 45 ends of the tool sections to dip into the water as they rotate, the centrifugal force throwing the water outward from the hot tube so as not to interfere therewith, and any water thrown off in this manner will 50 flow down the sides of the ring 48 into the bottom of the recess and out through the opening 72 made for that purpose.

It will be seen from the above description that my preferred method of corrugating hot tubes, which consists in alternately and momentarily gripping and releasing the tube along a helical line at a progressively shifting short length of the tube, may 55 be carried out by this machine.

While I have described with particularity the preferred embodiment of my improvements in tube-corrugating machines and process of corrugating tubes, it will be obvious to those skilled in the art, after understanding my invention, that various modifi- 60

cations and changes may be made therein without departing from the scope or spirit of the invention, and I aim in the appended claims to cover all such changes and modifications.

Having thus described my invention, what I claim as new and desire to secure by Letters Patent, is:—

1. In a machine for corrugating metal tubes, the combination of means rotative relative to the tube for momentarily gripping the tube along a helical line and releasing it one or more times successively during each relative rotation between the tube and said gripping means to form corrugations in the tube, and means for rotating said gripping means.

2. In a machine for corrugating metal tubes, the combination of means for rotating the tube, rotative means for momentarily and successively gripping the tube along a helical line and releasing it a plurality of times during each rotation of the tube to form corrugations in the tube, and means for rotating said gripping means relative to the rotating tube.

3. In a machine for corrugating metal tubes, the combination of means rotative relative to the tube for momentarily gripping the tube along a helical line and releasing it one or more times successively during each relative rotation between the tube and said gripping means to form corrugations in the tube, means for rotating said gripping means, and means for producing relative longitudinal movement between the tube and the gripping means.

4. In a machine for corrugating metal tubes, the combination of means for rotating the tube, means continuously operating to momentarily and successively grip the tube along a helical line and release it to form corrugations therein, means for rotating said gripping means relative to the rotating tube, and means for producing relative longitudinal movement between the tube and the gripping means.

5. In a device for corrugating metal tubes, the combination of a plurality of radial reciprocating tool sections each provided at its inner end with a longitudinal section of a helix having a plurality of convolutions, means for rotating said tool sections relative to the tube to be corrugated, and means co-operating with said sections to cause them to be reciprocated when rotated to momentarily grip and release the tube being corrugated.

6. In a device for corrugating metal tubes, the combination of a plurality of radial reciprocating tool sections each provided at its inner end with a longitudinal section of an internal thread having a plurality of convolutions decreasing in pitch and increasing in depth, means for rotating said tool sec-

- tions relative to the tube to be corrugated, and means coöperating with said sections to cause them to be simultaneously reciprocated when rotated to momentarily grip and release the tube being corrugated.
7. In a machine for corrugating metal tubes, the combination of a "swager" having rotative radially arranged tool sections, each tool section having a section of a helix formed on its inner end, said sections of the helix forming, when assembled, a helix increasing in depth and decreasing in pitch for momentarily gripping and releasing the tube, and means for producing relative rotation and longitudinal movement between the tube and the tool sections.
8. In a machine for corrugating metal tubes, the combination of a device having a plurality of radially movable tools, each having formed on its inner end a longitudinal section of a helical projection decreasing in pitch, means for continuously rotating and reciprocating said tool sections radially to cause them to continuously act to momentarily grip and release the tube along a helical line, and means for producing continuous relative rotation and longitudinal movement between the tube and said gripping means.
9. In a machine for corrugating metal tubes, the combination of means for continuously acting upon the tube to alternately and momentarily grip the tube along a helical line and release it to form corrugations therein, means for producing relative rotation between the tube and the gripping means, causing a twisting force in the finished portion of the tube, and a smooth mandrel extending beyond the gripping means and through the finished portion of the tube and of substantially the size of the inner diameter of the folded tube, upon which the tube is folded by the gripping means to protect the folds of the finished tube from distortion due to the twisting force.
10. In a machine for corrugating metal tubes, the combination of means for momentarily and successively gripping the tube along a helical line and releasing it to form corrugations therein, means acting upon the finished end of the tube for producing relative rotation between the tube and said gripping means, said gripping means acting to grip and release the tube one or more times during the formation of each convolution, means at the intake end of the gripping means for heating the tube, a hollow mandrel upon which the tube is folded by the gripping means, said mandrel being of substantially the size of the inner diameter of the finished tube, and means for cooling said mandrel.
11. In a machine for corrugating metal tubes, the combination of a device having a plurality of radially movable tools, each having formed on its inner end a longitudinal section of a helical projection decreasing in pitch, means for continuously rotating and reciprocating said tool sections radially to cause them to continuously act to momentarily grip and release the tube along a helical line, means for producing continuous relative rotation and longitudinal movement between the tube and said gripping means, and a mandrel of substantially the size of the inner diameter of the finished tube upon which the tube is folded by the gripping means.
12. In a machine for corrugating metal tubes, the combination of means for rotating the tube, a smooth mandrel secured to said means and to which the tube is secured at its forward end, said mandrel being substantially the size of the inner diameter of the finished tube, and means for momentarily gripping the tube along a helical line and releasing it, one or more times successively during each relative rotation between the tube and said gripping means, to fold the finished tube upon said smooth mandrel.
13. In a machine for corrugating metal tubes, the combination of a sectional corrugating tool acting continuously to momentarily and successively grip the tube along a helical line and release it to form corrugations therein, means for continuously producing relative rotation between the tube and said tool, and a smooth mandrel extending from the finishing end of the machine to the gripping means for protecting the folded tube, said mandrel being substantially the size of the inner diameter of the finished tube.
14. In a machine for corrugating metal tubes, the combination of means for momentarily and successively gripping a tube along a helical line and releasing it to form corrugations therein, means for producing relative rotation between the tube and said gripping means, said gripping means acting to grip and release the tube one or more times during the formation of each convolution, means at the intake end of the gripping means for heating the tube, a hollow mandrel upon which the tube is folded by the gripping means, said mandrel being of substantially the size of the inner diameter of the finished tube, and means for cooling said mandrel.
15. In a machine for corrugating metal tubes, the combination of means for continuously acting upon the tube to alternately and momentarily grip the tube along a helical line and release it to form corrugations therein, means at the intake end of the gripping means for heating the tube, a hollow mandrel upon which the tube is folded by the gripping means, and means for conveying a cooling fluid into said hollow mandrel to cool it.
16. In a machine for corrugating metal

tubes, the combination of means for continuously acting upon the tube to alternately and momentarily grip the tube along a helical line and release it to form corrugations therein, means at the intake end of the gripping means for heating the tube, means for rotating the forward end of the tube relative to said gripping means, a hollow mandrel secured to said rotating means and to which the forward end of the tube is secured, said mandrel extending from the finishing end of the machine toward the gripping means, and means for circulating a cooling fluid through said mandrel to cool the same.

17. In a machine for corrugating metal tubes, the combination of means acting continuously to momentarily and successively grip the tube along a helical line and release it to form corrugations therein, and means for producing relative rotation between the tube and said gripping means, said rotation-producing means including a yieldable connection.

18. In a machine for corrugating metal tubes, the combination of means for continuously acting upon the tube to alternately and momentarily grip the tube along a helical line and release it to form corrugations therein, and means for rotating the tube relative to the gripping means, said rotating means having a resilient connection which will momentarily yield when the tube is gripped by the gripping means and will move the tube forward during the moments of release.

19. In a machine for corrugating metal tubes, the combination of means for continuously acting upon the tube to alternately and momentarily grip the tube along a helical line and release it to form corrugations therein, and means for rotating the tube relative to the gripping means, said rotating means including a driving part, a driven part connected to the tube and a spring connection between the driven and driving parts which will permit the driven part to be retarded during the gripping moments.

20. In a machine for corrugating metal tubes, the combination of a rotary sectional corrugating tool having a plurality of reciprocating tool sections acting continuously to momentarily and successively grip the tube along a helical line and release it to form corrugations therein, means for rotating said sectional corrugating tool relative to the tube to be corrugated and means cooperating with said tool sections to cause them to be reciprocated when rotated to momentarily grip and release the tube being corrugated.

21. In a machine for corrugating metal tubes, the combination of a corrugating tool having a plurality of reciprocating tool sections adapted to act continuously to momen-

tarily and successively grip the tube along a helical line and release it to form corrugations therein and having a member with guides in which said reciprocating tool sections are mounted, means operatively related to said tool sections and rotative relative thereto to cause them to reciprocate in their guides and means for rotating the tube relative to the sections during the reciprocations.

22. In a machine for corrugating metal tubes, the combination of a corrugating tool having a plurality of reciprocating tool sections adapted to act continuously to momentarily and successively grip the tube along a helical line and release it to form corrugations therein and having a member with guides in which said reciprocating tool sections are mounted, means operatively related to said tool sections and rotative relative thereto to cause them to reciprocate in their guides and means for rotating the tube relative to the sections during said reciprocations, said means including a mandrel extending to the tool sections and to which mandrel the finishing end of the tube is secured, the diameter of said mandrel being substantially equal to the inner diameter of the corrugated tube.

23. In a machine for corrugating metal tubes, the combination of a rotary sectional corrugating tool having a plurality of reciprocating tool sections acting continuously to momentarily and successively grip the tube along a helical line and release it to form corrugations therein, means for rotating said sectional corrugating tool relative to the tube to be corrugated, means cooperating with said tool sections to cause them to be reciprocated when rotated to momentarily grip and release the tube being corrugated and means for rotating the tube comprising a mandrel extending through the sectional tool and to which the forward end of the tube is secured, the diameter of said mandrel being that of the inner diameter of the finished tube.

24. In a device for corrugating metal tubes, the combination of a plurality of radial reciprocating tool sections each provided at its inner end with a longitudinal section of a helix having a plurality of convolutions, means for rotating said tool sections relative to the tube to be corrugated, means cooperating with said sections to cause them to be reciprocated when rotated to momentarily grip and release the tube being corrugated, means for heating the tube, and means for conveying a cooling fluid to the tool sections to cool them.

25. The method of corrugating metal tubes, which consists in acting upon the tube to alternately and momentarily grip it along a helical line of progressively decreasing pitch and release it, while simultaneously

producing relative rotation between the tube and the gripping means.

26. The method of corrugating metal tubes, which consists in alternately and momentarily gripping and releasing the tube along a helical line of decreasing pitch at a progressively shifting short length of the tube.

27. The method of corrugating metal tubes, which consists in heating a progressively shifting portion of the tube and alternately and momentarily gripping and releasing a progressively shifting short length of the hot tube along a helical line of decreasing pitch.

28. The method of corrugating metal tubes, which consists in heating the tube and alternately and momentarily gripping and releasing the tube along a helical line of decreasing pitch at a progressively shifting 20 short length of the tube and protecting the convolutions of the finished tube from distortion.

In testimony whereof, I have signed my name to this specification, in the presence 25 of two subscribing witnesses.

LOUIS H. BRINKMAN.
